DESIGN FOR A MOTORCYCLE SADDLE BAG

John R. Hampel, Pewaukee, Wis., assignor to Milwaukee Saddlery Company, Milwaukee, Wis., a corporation of Wisconsin

Application June 25, 1947, Serial No. 139,909

Term of patent 3½ years

(Cl. D90—3)

To all whom it may concern:

Be it known that I, John R. Hampel, a citizen of the United States of America, and residing at Pewaukee, in the county of Waukesha and State of Wisconsin, have invented a new, original, and ornamental Design for a Motorcycle Saddle Bag, of which the following is a specification, reference being had to the accompanying drawings, forming a part thereof.

In the drawings:

Fig. 1 is a side elevational view of a motorcycle saddle bag, showing my new design;

Fig. 2 is a plan view of the motorcycle saddle bag;

Fig. 3 is a side elevational view of the front end of the motorcycle saddle bag.

Fig. 4 is a side elevational view of the back end of the motorcycle saddle bag.

I claim.

The ornamental design for a motorcycle saddle bag, as shown.

JOHN R. HAMPEL.
